Specification for Design.

Patented Nov. 23, 1920.

Application filed March 5, 1920. Serial No. 363,575. Term of patent 14 years.

To all whom it may concern:

Be it known that I, JOHN H. LICKERT, a citizen of the United States, residing at Evanston, in the county of Cook and State of Illinois, have invented a new, original, and ornamental Design for a Combined Pastry Knife and Server, of which the following is a specification, reference being had to the accompanying drawing, forming a part thereof.

The drawing shows a plan view and a side elevation view of a combined pastry knife and server showing my new design.

I claim:

The ornamental design for a combined pastry knife and server, as shown.

JOHN H. LICKERT.
